UNITED STATES PATENT OFFICE

JEAN ALBERT PERONY, OF SAINT-OUEN, FRANCE, ASSIGNOR TO SOCIETE D'OUTILLAGE
MECANIQUE ET D'USINAGE D'ARTILLERIE, OF SAINT-OUEN, FRANCE, A LIMITED
JOINT STOCK COMPANY OF FRANCE

ARRANGEMENT OF AUXILIARY BRUSHES FOR ROAD SWEEPING MACHINES

Application filed August 6, 1931, Serial No. 555,598, and in France March 10, 1931.

The present invention relates to a device applicable to sweeping machines and formed by one or more auxiliary brushes which among other uses can be employed for sweeping 5 road gutters or along houses.

The new device is essentially characterized by the feature that the auxiliary brushes are mounted upon horizontal spindles each carried by an arm pivoted to the frame of the 10 vehicle by means of a cross-shaped joint which makes it possible to set the axis of the auxiliary brush in a horizontal plane with a view to passing from a position of rest into a working position, and vice versa, while the 15 horizontal axis of the cross-shaped joint permits the brush to lift automatically when it meets an obstacle, and permits the auxiliary brush to be lifted by hand or mechanically for passing from a working position into a 20 position of rest, and vice versa.

In its preferred form of construction, the invention comprises an elastic or compressible element arranged in the transmission actuating each of the auxiliary brushes; this element permits the brush to move automatically 25 out of the way in a horizontal direction when it meets an accidental obstacle or strikes against a pavement when the vehicle is not correctly guided, and it also permits the brush 30 to be withdrawn into a position of rest and locked on the chassis of the vehicle.

The invention comprises other practical details of construction which will be described hereinafter.

One embodiment of the invention is illustrated by way of example in the accompanying drawings, in which:

Figures 1 and 1a form a partial plan view 40 of the frame of a sweeping machine of known type, and shows an auxiliary brush according to the present invention fitted to this type of vehicle. In this view, the automatic brush has been shown as being actuated by a transmission driven from the driving shaft of the 45 main brush, which shaft is assumed to be perpendicular to the longitudinal axial plane of the vehicle.

Figure 2 is a corresponding longitudinal elevation of a part.

Figure 3 is a longitudinal sectional eleva-

tion showing a practical form of construction of the auxiliary brush.

In these various figures, 1 is the frame of the vehicle, 2 is the driving fore-carriage, 3 is a casing in which is situated the shaft 4 for actuating the main brush and which will provide the power for driving the auxiliary brush or brushes. 55

Figures 4 and 5 shows in plan elevation respectively, partial view of a modification 60 of the device for preventing any direct impact between the shaft of the auxiliary brush and an obstacle such as the edge of a pavement, the side of a wall etc.

Each of these brushes is mounted upon a 65 horizontal shaft, *a* and this shaft is carried by an arm *b* connected to the frame of the vehicle by means of a cross-shaped pivotal joint *c* *d* comprising a vertical axis *c* and a horizontal axis *d*. By a movement about the 70 vertical axis *c*, the arm *b* and consequently the shaft *a* and the brush *e* carried by the latter can be made to pass from a position of rest into a working position. At the same time this axis permits the brush to move automatically 75 out of the way if it encounters a lateral obstacle when in use, the brush being returned into the normal working position by the provision of an elastic member in the transmission actuating the shaft *a*; in the 80 form of construction shown, this element is formed by an elastic link *i*—*j*—*k*.

Naturally the actuating transmission will comprise universal joints such as *m* and *h* between the shaft *a* and the shaft *n* connected 85 to a driving shaft 4 by a transmission gear *p*—*q*—*r*.

The horizontal shaft *d* of the cruciform joint *c*—*d* permits the brush shaft to be raised by hand or mechanically in order to 90 pass from the working position into the position of rest, and permits the brush to lift automatically when it encounters an obstacle preventing the rotation of the auxiliary brush. 95

For working purposes, the brush normally occupies the position shown in full lines in Figures 1 and 2. It may be withdrawn into a position of rest by movement about the cruciform joint *c*—*d* and be secured in 100

this position, by locking, for example, as shown in the drawings, by hooking on to a bracket f pivoted at f^1 to the frame. In this position the brush projects laterally by the least amount while at the same time it is moved out of contact with the ground, the causeway or other surface to be swept. The position the brush then occupies is partly indicated in dot-and-dash lines in Figure 1, the position of the arm b being also partly shown in dot-and-dash lines in Figure 2.

In order to prevent any direct impact between the shaft of the auxiliary brush and an obstacle such as a pavement edge or the side of a wall etc., during the work, a disc g is fitted or screwed on the outer end of this shaft, upon which disc is loosely mounted a buffer ring g^1 . The free rotation of the ring g^1 thus efficiently damps the impact which would otherwise be transmitted directly to the brush shaft.

In order to facilitate the working of the brush on a horizontal axis, it may, according to the invention, be provided on its outer end with a brush element of suitable width and having, as shown in Figure 3, a larger diameter than the body of the brush. This increase in diameter may be obtained as in the example shown in Figure 3, by tufts of greater length. It may also be obtained by keeping the length of the tufts uniform and in this case giving the support e a suitable profile.

Naturally, when tufts of different lengths are employed, a brush element having the desired greater diameter may be fitted to the end of the support carrying a body having tufts of smaller diameter.

According to the modification shown in Figures 4 and 5, instead of mounting a buffer ring g^1 on the disc carried by the shaft a of the auxiliary brush, as shown in Figure 3, a shock absorbing roller or disc or any other similar member s is mounted on an arm t adjustable in position on the arm b which supports the shaft of the auxiliary brush.

In the example shown in Figures 4 and 5, the spindle s^1 of the roller s is carried by a bracket s^2 which may be given a varying inclination with respect to a supporting base t^1 formed at the end of the arm t . Bolts s^3 movable in slots t^2 in the base t^1 permit the bracket to be locked in the chosen position of adjustment. The height at which the roller s is placed may also be regulated. For this purpose the arm t , as shown in Figure 5, carries at its upper end a boss or head t^3 which can be locked in various positions by adjusting bolts t^4 carried by the said boss in slots b^2 and a yoke b^1 itself movable upon an arm b .

As will be seen, the device described permits three adjustments to be made by the displacement of the supporting yoke b^1 on the

arm b , the displacement of the arm t on the yoke b^1 in a vertical direction and the varying inclinations of the base s^3 with respect to the yoke t^1 . It goes without saying that the constructional details of the shock absorbing member, adjustable in position, and of its support may vary. Thus for example, an elastic suspension may be provided for the pivot s^1 of the bracket s .

I claim:

1. A street sweeping machine having a vehicular frame and a source of power mounted thereon, a supporting arm having journalled in one extremity thereof a substantially horizontal shaft, a brush mounted on said shaft, a cruciform pivotal coupling connecting the other extremity of said arm to said vehicular frame whereby said arm is capable of movement in both a horizontal and a vertical plane, and means for driving said brush shaft from said source of power including a main drive shaft extending transversely of said frame, an auxiliary drive shaft parallel to said main drive shaft and operatively connected thereto, and a telescoping transmission shaft operatively connected to said auxiliary drive shaft and to the shaft of said brush by universal joints, said transmission shaft having means normally tending to elongate it to urge said brush shaft and brush outward from said vehicular frame to sweeping position and also permitting inward movement of said brush out of the way of obstacles and to inoperative position without affecting the drive thereof.

2. A street sweeping machine having a vehicular frame and a source of power mounted thereon, an L-shaped supporting arm having journalled in one extremity thereof a substantially horizontal brush shaft, a brush mounted on said shaft, a cruciform pivotal coupling connecting the other extremity of said arm to said vehicular frame whereby said arm is capable of movement in both a horizontal and a vertical plane, means for driving said brush shaft from said source of power including a telescoping transmission shaft having resilient means interposed between the telescoping portions whereby the brush shaft and brush are normally urged outward to sweeping position and the driving transmission is maintained regardless of the movement of said brush shaft relative to said source of power, and a supporting bracket swivelly mounted on said frame in position to engage and support said arm when the latter is moved inward and upward to place said brush in inoperative position.

3. In a street sweeping machine, a brush, a shaft on which said brush is mounted, one end of said shaft projecting outwardly beyond the brush in position where it may encounter obstacles during the sweeping operation, and means for preventing injury to said

shaft by contact with said obstacles comprising a disc rigidly secured to the outer end of said shaft, and a buffer ring rotatably mounted on the periphery of said disc.

4. In a street sweeping machine, a brush, a shaft on which said brush is mounted, one end of said shaft projecting outwardly beyond the brush in position where it may encounter obstacles during the sweeping operation, a supporting arm in one extremity of which said brush shaft is journaled, the other extremity of said arm being connected to the body of said machine, and means for preventing injury to said brush shaft by contact with said obstacles comprising a substantially vertical roller carrying arm, a clamp for adjustably securing said arm to said supporting arm at a variable horizontal distance from said brush shaft, means for varying the vertical position of said roller carrying arm with respect to said clamp, a supporting yoke formed at the lower end of said roller carrying arm, a bracket, a shock absorbing roller rotatably mounted on said bracket, and means for securing said bracket to said yoke in a plurality of angular positions whereby the inclination of the axis of rotation of said roller may be varied.

In testimony whereof I have signed this
30 specification.

JEAN ALBERT PERONY.
